X-RAY UNIT

Robert H. Ensign, Bronxville, and Alban Gifford Jackson,
New York, N. Y., assignors to Ritter Company, Inc., a
corporation of Delaware

Application November 13, 1956, Serial No. 43,722

Term of patent 14 years

(Cl. D61—1)

Fig. 1 is a perspective view of an X-ray unit showing our new design; and

Fig. 2 is a fragmentary perspective view showing portions of the unit of Fig. 1 with the head member swung through approximately 180° from the position shown in Fig. 1.

Fig. 3 is a fragmentary rear perspective view thereof, showing the head member swung through approximately 270° from the position shown in Fig. 1.

The essential features of our design reside in the solid line portions.

We claim:

The ornamental design for an X-ray unit, substantially as shown and described.
